UNITED STATES PATENT OFFICE.

CYRIL P. BROWN, OF SPRING LAKE, MICHIGAN.

LEAF-TURNER.

SPECIFICATION forming part of Letters Patent No. 431,327, dated July 1, 1890.

Application filed December 12, 1889. Serial No. 333,432. (No model.)

To all whom it may concern:

Be it known that I, CYRIL P. BROWN, of Spring Lake, in the county of Ottawa and State of Michigan, have invented a new and 5 Improved Leaf-Turner, of which the following is a full, clear, and exact description.

My invention relates to a device for turning the leaves of book or sheet music, or books or manuscripts of any kind; and the invention has for its object to provide a simple, inexpensive, and efficient instrument of this class which will positively turn the leaves either way through the medium of a conveniently-located lever, which may be actuated 10 by a careless stroke of the hand. The instrument is adapted for attachment to either a vertical or horizontal surface, which it will not mar, and may be folded into comparatively small compass when out of use.

The invention will first be described, and then will be particularly pointed out in the claims.

Reference is to be had to the accompanying drawings, forming a part of this specification, in which similar letters of reference indicate corresponding parts in all the figures.

Figure 1 is a front elevation of my improved leaf-turner with the music holder or clamp partly broken away. Fig. 2 is a plan view 25 with the music-clamp in horizontal section on the line $x-x$ in Fig. 1. Fig. 3 is a bottom plan view of the instrument. Fig. 4 is a central sectional side view, showing the leaf-turner held to a nearly-vertical music-rack or 30 musical-instrument front by means of a screw fixed to the rack or front. Fig. 5 is a like view showing the leaf-turner held by a clip fastened to the horizontal ledge of a music-rack or musical instrument. Fig. 6 is a front 35 view of one of the leaf-turning arms with the leaf-holding wire or clip folded down as when out of use; and Fig. 7 is a detail perspective view of the joint between one of the turning-arms and its leaf-clip.

The main or base plate A of the leaf-turner 45 is formed or provided with a couple of upper forwardly-projecting arms B B, one near each end, and which form rests for the book or sheet-music the leaves of which are to be turned. At its central rear portion the plate 50 A is provided with an upwardly-projecting tongue or lip a, which is preferably provided

with a slot a', made larger at its lower end, to receive a headed screw for holding the leaf-turner to a practically vertical wall or support, as hereinafter more fully explained. This tongue a is provided at opposite edges with bent flanges a² a², forming a way or groove to receive the foot c of a sheet-music clamp or holder C. This music-clamp consists simply of two plates c' c², of any suitable material, sheet metal being preferred, and to one of which the foot c is fixed. Both plates are pressed to or toward each other by elastic clips c³ c³, of Ω form, fixed to them. The upper ends of the clamp-plates are bent outward at c⁴ c⁴ to allow sheet-music to be easily and quickly slipped between the plates to clamp it firmly at the back and allow the leaves to be turned either way by the leaf-turning arms, as hereinafter described.

I provide the base-plate A with three buffers a³ a³ a⁴ to protect either a vertical support, such as a music-rack, or a horizontal support, such as a ledge or shelf on a music-rack or piano or other musical instrument. These buffers are made preferably of rubber, and the ones a³ a³ are placed one near each end of the base-plate, and consist, preferably, of a single piece of rubber slit to receive or straddle the plate, while the other centrally-disposed buffer a⁴ is a rubber plug fitted tightly into a hole made in the base-plate tongue a above or beyond its slot a', and in such position relatively to the end buffers a³ a³ that the entire leaf-turner will stand steadily on the three buffers upon any flat nicely-finished surface, as a piano or table-top, without marring it. The base-plate is also provided with a lower forwardly-extending tongue a⁵, which is provided at its opposite edges with bent flanges a⁶ a⁶, forming a way or groove to receive the outer end of a simple metal clip D, which will be held by a screw d to a horizontal ledge of a music rack or instrument.

In Fig. 4 of the drawings the base-plate, and consequently the entire leaf-turner, is held to the vertical face of a music rack or holder E by slipping the larger lower end of the base-plate slot a' over the head of the screw e and then letting the base-plate down until the ends of the buffers a³ a³ rest on the ledge e' of the support, at which time the narrow part of the slot a' will be behind the

screw-head to retain the leaf-turner, the three buffers a^3 a^3 a^4 then resting flat against the support E to prevent marring its face.

- In Fig. 5 of the drawings the leaf-turner is sustained from the flat support F by simply engaging the base-plate flange-guides a^6 with the upbent outer end of the clip-plate D, while the lower ends of the two buffers a^3 a^3 rest on the support to prevent marring it.
- 10 To the central part of the base-plate A are fixed a parallel pair of arched bracket-plates G G, which project forward face to face a slight distance apart to receive and guide between them the sheet-metal hook-plate II, having two opposite hooks h h' , with lips or projections h^2 h^2 in front of them. This duplex hook-plate, which works freely edgewise between the brackets G G, is pivoted by a pin or screw h^3 , at the outer end of its bent stem 20 or arm h^4 , to the outer part of a key-lever I, which at its inner end is fulerumed or pivoted by a pin or screw i to the base-plate flange or tongue a^5 .
- A forked spring J, which is held preferably by a screw j to the center of the key-lever, has two arms or limbs j' j^2 , which have upturned extremities, which pass through holes or slots i' i^2 made in the key-lever, and press against opposite sides or edges of said lever, 25 preferably at points not far removed from the pivot h^3 of the duplex hook-plate II. This spring J performs two important functions—viz., it returns and holds the duplex hook-plate II to normal central position after the 30 key-lever is returned to central position, and it also causes the hooks h h' to positively engage the outermost leaf-turning arm after the shoulder h^2 in front of either hook passes by said arm, as hereinafter more fully explained.
- 35 The key-lever I is returned to normal central position, preferably by a spiral spring K, which is held at one end of the fastening-screw j of the spring J, and at its other end engages a hook k , fixed to the lower flange or tongue a^5 of the base-plate. The key-lever is provided with a finger plate or head i^3 , bent into vertical plane and allowing easy and convenient operation of it by a careless stroke of the finger or hand.
- 40 Before the arched brackets G G are fixed to the base-plate A the eyes or loops l of a series of leaf-turning arms L are slipped into them, so as to be held to the outer U-shaped portions g of the brackets. These arms L are also provided at one edge and outside their eyes or loops l with a tongue or finger l' , thereby forming a slot or groove l^2 between the tongue and the body of the arm to receive the duplex hook-plate II. The base of the 45 arm-slot l^2 is separated from the arm-loop l by a cross-piece l^3 , onto which either of the hooks h h' of the plate II may act to swing the arm to one side or the other, and during either swinging movement of the arm the engagement of its slot l^2 with the hook-plate II 50 will cause the arm to move practically in the same plane, and will also hold the arm well

up into proper position to positively support the leaf as it is turned and before and afterward. The leaf is held by a wire finger-piece 70 or clip attached to the outer end of the arm, as presently explained. It will be noticed that the hook-plate II has a continuous round main body portion cut away at the interior to form the hooks h h' and the adjacent lips or 75 projections or shoulders h^2 h^2 , and that the inner part of the plate, and, in fact, its whole head or body portion, always works between the two brackets G G, which thus sustain the hook-plate flatwise and enable it to always 80 form an efficient guide and support for the slotted leaf-turning arms, which are fitted to it, as above described.

The music-leaf fingers or clips M are peculiarly made of one piece of wire by bending 85 it over double at the center to form a cross-piece m , and then bending the wire at right angles to the cross-piece m to form eyes or loops m' m' , which fit one at each face of the leaf-turning arm L, and from these two eyes 90 the wire is bent outward to form two parallel fingers m^2 m^2 , between which the music-leaf is slipped and held. The entire clip is pivoted to the outer end of the arm L by a suitable pin m^3 , and at one edge the arm is provided with a recess m^4 , into which the cross-piece m enters and stops when the clip is folded down parallel with the arm, as shown in Fig. 6 of the drawings, and when the clip is opened back or unfolded from the arm into 95 position for use the cross-piece m comes to a stop against the edge of the arm to brace the clip in proper working position, as most clearly shown in Figs. 1, 2, 3, and 7 of the drawings.

100 The operation of the leaf-turning instrument is very simple and efficient, as follows: When the instrument is held to a music-rack or to a piano or organ by means of the screw e or clip D, as shown in Figs. 4 and 5 of the 110 drawings, the music, if a book, will be rested on the arms B B, or, if in sheets, will be placed in the clamp C, and when the leaves are slipped into the outturned or unfolded 115 arm-clips M the instrument is ready to turn the clipped leaves in either direction by simply pressing or throwing the key-lever I to one side or the other. We will suppose that all the arms L M holding the music-leaves are 120 swung over to the left-hand side of the instrument. In this case when the key-lever I is thrown over toward the right hand the double hook-plate II will be also swung on its pivot h^3 in a peculiar manner, and the shoulder h^2 next the hook h' will ride over 125 the cross-bars l^3 of all the inside arm-loops l to prevent engagement of said hook with them; but as the shoulder passes by the loop cross-bar of the outermost arm L the limb or arm j' of the spring J will instantly swing 130 the hook h into engagement with the cross-bar l^3 of the outer arm and cause this arm only and the leaf held by its clip M to be quickly turned over to the right hand as the

arm-loop l swings around on the parts g of the bracket-supports G . When the key-lever is released, the spring K restores it and the hook-plate H to normal intermediate positions, and the next time the key-lever is swung over to the right hand the next outer arm and attached leaf will in like manner be turned over by the hook h of the plate H toward the right. It is obvious that when the key-lever I is swung over toward the left hand the outer arm L , then at the right-hand side of the instrument, will be engaged by the hook h of the plate H , the limb j^2 of the spring J then engaging said hook with the cross-bar β of the arm-loop to swing the arm and attached leaf back again to the left hand. The music-leaves may thus be quickly and positively turned either to the right or left hand by throwing the key-lever to the right or left and without the least danger of turning more than one leaf at a time, or of failure in turning a leaf when the key-lever is operated, even though it be thrown over by a careless stroke of the hand.

Having thus described my invention, I claim as new and desire to secure by Letters Patent—

1. In a leaf-turner, the combination, with a support or base-plate and a guide, of leaf-turning arms placed loosely on the guide, a key-lever fulcrumed to the support, a hook-plate carried by the key-lever and having a shoulder next the hook, and a spring normally throwing the hook into engagement with the outermost leaf-turning arm as the key-lever is operated, substantially as herein set forth.

2. In a leaf-turner, the combination, with a support or base-plate and a guide, of leaf-turning arms placed loosely on the guide, a key-lever fulcrumed to the support, a plate carried by the key-lever and provided with two opposite hooks and adjacent shoulders, and two spring-arms acting on the hook-plate and causing engagement of either hook with a leaf-turning arm as the key is operated, substantially as herein set forth.

3. In a leaf-turner, the combination, with a support or base-plate and a guide, of leaf-turning arms placed loosely on the guide, a key-lever fulcrumed to the support, a hook-plate carried by the key-lever and having shoulders next the hooks, a spring normally throwing the hook or hooks into engagement with the outermost arm as the key-lever is operated, and a spring retracting the key-lever and hook-plate to normal intermediate positions, substantially as herein set forth.

4. In a leaf-turner, the combination, with a support or base-plate and a guide, of leaf-turning arms placed loosely on the guide, a key-lever fulcrumed to the support, a plate carried by the key-lever and provided with two opposite hooks and adjacent shoulders, a spring normally engaging each hook with the outermost arm as the key-lever is operated, and a spiral spring K , held to the key-lever and support and retracting the lever and

hook-plate to normal positions, substantially as herein set forth.

5. In a leaf-turner, the combination, with a support or base-plate and a bracket-guide thereon, of a series of leaf-turning arms held loosely to the guide, a key-lever fulcrumed to the support, a hook-plate pivoted to the key-lever and having a continuous rounded head cut away at the interior to form opposite hooks h h' and adjacent shoulders h^2 , and a spring normally throwing the hooks into engagement with the outermost leaf-turning arm as the key-lever is operated, substantially as herein set forth.

6. In a leaf-turner, the combination, with a support or base-plate and two bracket-guides thereon, of a series of leaf-turning arms looped to said guides, a key-lever fulcrumed to the support, a hook-plate pivoted to the key-lever and lying between the two guides and provided with hooks h h' and adjacent shoulders h^2 , and a spring normally throwing either hook into engagement with the outermost leaf-turning arm as the key-lever is operated, substantially as herein set forth.

7. In a leaf-turner, the combination, with a support or base-plate and a guide thereon, of a key-lever fulcrumed to the support, a series of leaf-turning arms held to the guide, a shouldered hook-plate pivoted to the lever, and a spring normally throwing the hook or hooks of said plate into engagement with the outermost leaf-turning arm as the key-lever is operated, said leaf-turning arms each having a slot into which the hook-plate enters to steady the arms in their swinging movements and sustain them when adjusted, substantially as herein set forth.

8. In a leaf-turner, the combination, with a support or base-plate and two bracket-guides thereon, of a key-lever fulcrumed to the support, a series of leaf-turning arms looped at their inner ends around the two guides, a shouldered hook-plate pivoted to the key-lever and held between the two guides, and a spring normally throwing the hook or hooks into engagement with the outermost leaf-turning arm as the key-lever is operated, said leaf-turning arms each having a slot into which the hook-plate enters, substantially as described, for the purposes set forth.

9. In a leaf-turner, the combination, with the swinging leaf-turning arms, of leaf-clips held to their outer ends and formed with a cross-bar m , two adjacent side loops or eyes m' m'' , through which passes the pivot holding the clip to the arm, and two leaf-receiving fingers m^2 m^3 , extending from the pivot-eyes, substantially as herein set forth.

10. In a leaf-turner, the combination, with the swinging leaf-turning arms having an edge recess m^4 , of leaf-clips held to the arms and formed with a cross-bar m , two adjacent side loops or eyes m' m'' , through which passes a pivot holding the clip to the arm, and two fingers m^2 m^3 , extending from the pivot-eyes, said clips adapted to fold to the arms, at which

time the cross-piece m enters the arm-recess m^4 , and adapted also to be unfolded when the cross-piece forms a stop against the arm, substantially as herein set forth.

- 5 11. In a leaf-turner, the supporting base-plate made with a screw-receiving slot a' in its upper part, and with clip-receiving flanges or openings a^6 at its lower portion, substantially as described, whereby the leaf-turner 10 may be held by a headed screw or pin to a vertical support and by a clip to a horizontal support, substantially as herein set forth.
12. In a leaf-turner, the combination, with the support or base-plate, of two end cushions 15 a^3 a^3 and a center cushion a^4 , disposed to prevent marring of a vertical or horizontal support, to which the leaf-turner may be held, and adapted also to sustain the instrument on a flat surface, substantially as herein set 20 forth.

13. In a leaf-turner, the combination, with the support, a base-plate provided with an

upper socket, and leaf-turning arms and operating mechanism held to the support, of a detachable sheet-music clamp consisting of 25 two plates, one having a foot adapted to the base-plate socket, and spring-clips pressing the clamp-plates toward each other, substantially as herein set forth.

14. In a leaf-turner, the combination, with 30 the support or base-plate having an upper tongue a , provided with side flanges a^2 a^2 , forming a socket, and leaf-turning arms and operating mechanism held to the support, of a detachable sheet-music clamp C, consisting 35 of two plates c' c^2 , having outturned upper ends c^4 c^4 , the plate c' having a foot c , adapted to the flanges a^2 , and spring-clips c^3 , held to the plates and pressing them toward each other, substantially as herein set forth.
